Primary Examiner — Susan Bennett Hattan*Assistant Examiner* — Suzanne E Tisdell(74) *Attorney, Agent, or Firm* — Akerman LLP(57) **CLAIM**

The ornamental design for a grill hood, as shown and described.

DESCRIPTION

FIG. 1 is a perspective view of the “grill hood” showing my new design, with variable width indicated with the use of a break line;

FIG. 2 is a top view thereof;

FIG. 3 is a bottom view thereof;

FIG. 4 is a left side view thereof;

FIG. 5 is a right side view thereof;

FIG. 6 is a back view thereof; and,

FIG. 7 is a front view thereof.

The broken lines show unclaimed environmental structures.

1 Claim, 7 Drawing Sheets(56)
